(57) **CLAIM**

The ornamental design for a wipe warmer, as shown and described.

DESCRIPTION

FIG. 1 is a perspective view of a wipe warmer;

FIG. 2 is a front view thereof;

FIG. 3 is a rear thereof;

FIG. 4 is a left view thereof;

FIG. 5 is right view thereof;

FIG. 6 is a top thereof; and,

FIG. 7 is a bottom view thereof.

The broken lines shown in the drawings depict portions of the wipe warmer that form no part of the claimed design. The oblique line shading shown in FIGS. 1-2 and 6 depicts a transparent or translucent surface
